FUSE CONSTRUCTION

William O. Schultz, South Milwaukee, Wis., assignor to McGraw Electric Company, a corporation of Delaware

Application November 6, 1943, Serial No. 509,160

15 Claims. (Cl. 200—126)

1

This invention relates to fuse constructions and while it is particularly applicable to repeating fuse constructions, nevertheless certain phases of the invention are equally applicable to single type fuse constructions as will appear hereinafter.

In fuse devices as heretofore made it has been the usual practice to provide transfer switches which transfer the circuit from one fuse to another fuse after the first fuse has blown, and to provide time delay means for delaying the action of the transfer switches. However, in the devices as heretofore made it has been necessary to open the service line at a point in advance of the fuse construction whenever any adjustment of the time delay mechanism was required.

This invention is designed to overcome the above noted defect and objects of this invention are to provide a fuse construction of the drop-out type in which time delay means is provided which may be adjusted without opening the service line ahead of the fuse construction, the construction of the present invention being such that the time delay means is electrically dead after the fuse tube, in the case of a single fuse tube construction, or the fuse tubes, in the case of a repeating fuse tube construction, have dropped to open position.

Further objects are to provide a fuse construction in which a simple type of time delay means has been provided which delays the drop-out motion of the fuse tube and allows the circuit to be cleared within the fuse tube prior to the time that the terminal of the fuse tube moves away from the stationary terminal to thereby avoid arcing at the terminals.

In greater detail objects of this invention are to provide a repeating fuse construction of the drop-out type in which the transfer switches are located at the top of the device to successively connect the stationary upper terminals after the corresponding fuse tube has moved outwardly to inoperative position, in which time delay means is provided which controls the tube, the tube being arranged to control the transfer switch, in which this time delay means is located adjacent the lower portion of the fuse construction and is, as stated, electrically dead when the fuse tubes have all dropped or been moved to inoperative position, and to provide means whereby the time delay means may be adjusted if desired.

Further objects are to provide a drop-out fuse construction in which time delay means is provided for delaying the drop-out action of the fuse tube but in which quick acting flip-out means have been provided which acts independently of the motion of the fuse tube, which operates while the fuse tube remains in its opera-

2

tiye position to quickly withdraw any remaining portion of the fuse link from the fuse tube.

Further objects are to provide a drop-out fuse construction in which heavy contact pressure is secured between the upper stationary terminal and the upper terminal of the fuse tube, and in which no flexible leaders are required, and in which heavy contact pressure is secured between the transfer switch and the stationary contacts engaged by the transfer switch, and specifically to provide spring means for actuating the transfer switch which is so organized that it exerts its minimum effective pressure when the transfer switch is open and thus reduces friction at the upper end of the fuse tube and its maximum effective pressure when the transfer switch is closed to secure high contact pressure for the transfer switch.

Further objects are to provide a fuse construction in which a quick acting flip-out means is provided which not only withdraws any remaining portion of the fuse link from the fuse tube but releases the fuse link and allows it to be thrown or dropped from the fuse device.

Embodiments of the invention are shown in the accompanying drawings, in which:

Figure 1 is a side elevation of a repeating fuse construction.

Figure 2 is a front elevation with the first fuse removed and with a part broken away.

Figure 3 is a sectional view on the line 3—3 of Figure 2.

Figure 4 is a sectional view on the line 4—4 of Figure 2.

Figure 5 is a sectional view of the time delay means, such view corresponding to a section on the line 5—5 of Figure 3.

Figure 6 is a sectional view similar to Figure 3 with fewer of the parts shown in section and showing the fuse tube in the position it occupies in an early stage of its drop-out motion.

Figure 7 is a view of the lower portion of a fuse tube showing a further form that the invention may take.

Figure 8 is a sectional view on the line 8—8 of Figure 7.

Figure 9 is a view of the lower portion of a fuse tube showing a further form that the invention may take.

Figure 10 is a sectional view on the line 10—10 of Figure 9.

Referring to Figures 1 to 6 showing the first form of the invention, it will be seen that the repeating fuse construction comprises a plurality of upper terminals indicated generally by the reference characters 1, 2 and 3 which are mounted on an insulating bar or member 4. The insulating member 4 is provided with a pair of outwardly projecting barriers 5 located between successive upper terminals. A plurality of lower

terminals are provided and are indicated generally by the reference characters 6, 7 and 8. One of these lower terminals, for instance the terminal 6, may be provided with a connecting tab or member 9 to which the load is connected. All of the lower terminals 6, 7 and 8 are connected by a conducting bar 10. The power line is connected, as indicated in Figure 2, to the first upper terminal 1. The upper insulating bar 4 and the lower connecting bar or member 10 are carried respectively by means of insulators 11 and 12 secured to a supporting channel iron or member 13. The member 13 is adapted to be secured to any suitable support.

A plurality of drop-out fuses 14, 15 and 16 are pivotally carried by the lower terminals 6, 7 and 8 respectively and normally are electrically connected to the upper terminals 1, 2 and 3. These fuse tubes are adapted to successively drop out of position on overload and transfer switches are provided between successive upper terminals. Time delay means is provided for delaying the drop-out action of all of the fuse tubes as will be described in detail hereinafter.

The upper terminals are each provided with a cam like member 17 which is provided with downwardly slanting side faces and which is formed integral with the corresponding terminal member. A generally U-shaped spring contact arm of relatively heavy material is indicated at 18 and is loosely pivotally held by the terminal member and constitutes a part of the terminal member. The side arms of this U-shaped spring member 18 tend to move towards each other and grip the cam member 17 therebetween. The spring arms coat with the cam member 17 and urge the spring arms downwardly. They normally rest against outwardly projecting pins 19 forming a portion of the upper terminal 20 of the corresponding fuse tube. The arms 18 are provided with downwardly depressed portions 21 behind which the pins 19 are normally positioned, the arms therefore acting as yielding latches to hold the corresponding fuse in operative position. The outer ends of the arms 18 are upwardly and outwardly flaring as indicated at 22 to assist in guiding the fuse into place when it is being rocked to closed position after having been refused. The U-shaped spring arms 18 are positioned beneath an overhanging portion of the corresponding terminal and are loosely held by means of the upwardly turned lip 23 integral with the corresponding terminal. The lip 23 is malleable and is bent upwardly at its end, as shown in Figure 1, after the spring arms 18 have been placed in position. The spring arms 18, therefore, have free pivotal action with respect to the corresponding upper stationary terminal and have a firm and good electrical contact with the side walls of the cam member 17 and also have a firm and good electrical contact with the pins 19 of the upper terminal of the fuse tube, thus providing excellent electrical connection between the upper terminal of the fuse tube and the corresponding upper stationary terminal.

It is to be noted that when a tube drops from operative to inoperative position, the spring arms 18 ride downwardly on the cam member 17 and come to rest when they engage the outwardly projecting portions 24 formed integrally with the cam member 17. The details of the construction of the upper contact including the spring arms are more fully described in my Patent No. 2,357,772 of September 5, 1944, for Cut-Out Construction.

5 The upper stationary contacts 1 and 2 differ from the upper stationary contact 3 in that each of the upper stationary contacts 1 and 2 is provided with a transfer switch mechanism. This transfer switch mechanism comprises a main operating lever 24 which, as may be seen from Figure 3, is pivoted as indicated at 25 within the upper portion of a hood 26 integral with the corresponding upper stationary contact. The lever 26 is provided with two integral arms, as may be seen from the dotted line illustration in Figure 2, and is provided with a laterally projecting integral extension 27 at the lower end of the lever.

10 A plungerlike member 28 is provided with a bifurcated rear end which is mounted between the arms of the lever 24 and is pivoted to such arm by means of the pivot pin 29, as shown in Figure 3. A spring 30 extends between the pivot pin 29 and a stationary pin 31 carried by the hood 26 and the spring 30 tends to rock the lever 24 in a counterclockwise direction. It is resisted, however, as the plunger 28 is held inwardly because the head 32 of the plunger engages the upper terminal of the fuse tube when the fuse tube is in operative position as shown in Figure 3.

15 The plunger 28 extends through a downward extension of the cam member 17 and is guided thereby. The head 32 may be made separate from the plunger and may be secured thereto by means of a screw or in any other suitable manner as shown in Figure 2. The transfer switch is pivoted to the lateral extension 27 and is indicated by the reference characters 33, 34 and shown most clearly in Figure 4. This transfer switch is provided with a long arm 33 and a short arm 34. Each of the arms 33 and 34 is provided with ball like contact portions at their ends which are adapted to engage portions of the stationary upper contacts of successive fuses to thereby transfer the circuit from one upper stationary contact to the next adjacent stationary contact in a manner hereinafter to appear.

20 The plunger 28 extends through a downward extension of the cam member 17 and is guided thereby. The head 32 may be made separate from the plunger and may be secured thereto by means of a screw or in any other suitable manner as shown in Figure 2. The transfer switch is pivoted to the lateral extension 27 and is indicated by the reference characters 33, 34 and shown most clearly in Figure 4. This transfer switch is provided with a long arm 33 and a short arm 34. Each of the arms 33 and 34 is provided with ball like contact portions at their ends which are adapted to engage portions of the stationary upper contacts of successive fuses to thereby transfer the circuit from one upper stationary contact to the next adjacent stationary contact in a manner hereinafter to appear.

25 A spring 35 extends between lips carried by the arm 33 and the laterally projecting portion 27 of the lever 24. The spring 35 is a lighter spring than the spring 30 and normally biases the transfer switch towards open position. The effect of the spring 35 is overcome when the plunger 28 is released and the spring 30 overpowers the action of the spring 35. It is to be noted from reference to Figure 3 that when the fuse tube drops out and the plunger 28 is released, the spring 30 will rock the lever 24 in a counterclockwise direction as viewed in Figure 3 and its effective lever arm will increase as the lever 24 rocks outwardly. Thus an increasing force is applied by the spring 30 when the spring is free to act and this increasing force is utilized, as will appear hereinafter, to secure a high contact pressure 30 and to exert a greater force on the transfer switch when the switch is in closed position than when the switch is in open position due to the increasing effective lever arm.

30 It is to be noted from Figure 3 that when the parts are in the position shown, the spring 30 has its minimum effective lever arm and consequently the force exerted by the plunger 28 is a minimum. This reduces the friction produced at the upper terminal of the fuse tube between the projecting pins 19 and the depressed portions 21 of the spring arms 18, see Figure 1.

35 It is to be noted from reference to Figures 2 and 4 that the stationary contacts 1 and 2 are provided with contact members 36 which form downward extensions of the cam members 17.

Also from reference to Figures 3 and 4 it will be seen that the stationary terminals 2 and 3 are also provided with an additional contact portion or member 37. Normally the transfer switches are in open position as shown for the right-hand switch of Figure 4. However, when the first tube 14 drops outwardly as a result of over-load following rupture of its fuse link, the plunger 28 is released and moves outwardly, thus allowing the lever 24, see Figure 3, to rock outwardly, 10 the effective lever arm through which the spring 30 acts on the lever 24 increasing as the lever 24 rocks outwardly. This outward rocking of the lever 24 carries its integral extension 27 outwardly and moves the transfer switch to the position shown for the left-hand transfer switch of Figure 4. The end of the short arm 34 rides on the contact member 36 and the end of the long arm 33 engages the contact member 37 of the upper stationary contact 2. A high contact pressure is secured at each end of the transfer switch 33, 34 and direct electrical connection is made between the contact member 36 of the first upper stationary terminal 1 and the contact member 37 of the second upper stationary terminal 2. The upper stationary terminal 3 is not provided with any transfer switch but is provided with the contact member 37 adapted to be engaged by the end of the transfer switch of the second upper stationary terminal 2 when the fuse tube 15 has 30 rocked downwardly to inoperative position.

It is clear from the description thus far given that no flexible leaders are required between any upper stationary contact and the spring arms 18 nor is any flexible leader required in association with the transfer switches. The fuse tubes are each adapted to have a fuse link extending therethrough provided with a flexible leader 38, a fusible section 39 and a button head 40 at its upper end. Any suitable type of fuse link may, however, be employed.

The upper terminals of the fuse tubes may be provided with any suitable means for clamping the button head in place and for securing good electrical contact therewith. For instance, the upper terminal of each fuse tube may be provided with a pair of levers 41 and 42 which grip the button head 40 between them. The lever 41 may be provided with a U-shaped member 43 through which a thumb screw 44 is threaded, the thumb screw being adapted to bear against the lever 42 and to thus clamp the button head in place. The engaging surface of the levers 41 and 42 may be upwardly slanting so as to facilitate the outward blowing of the button head of the fuse link upon very high overloads. Normally the head of the fuse link is not blown from the fuse tube under moderate or small overloads but, under heavy overloads the fuse tube allows venting at both ends. This construction is set forth in detail in my Patent No. 2,357,772 hereinbefore referred to.

Adjacent their lower ends the fuse tubes each carry a rigid, rearwardly and downwardly extending arm 45 which may include a split sleeve portion 46 which is held clamped and locked to the lower portion of the fuse tube by means of the bolt 47, such bolt also fitting in a transverse groove formed in the fuse tube to prevent inadvertent turning of the fuse tube with reference to the clamping sleeve 46 and arm 45. The arm 45 is in reality two spaced arms. The supporting arm structure 45 composed of the two arm portions is pivoted as indicated at 48 to the main lever 49. The main lever is provided with trun-

nions 50 which are removably received within the hook-like supports 51 of the lower terminal member.

The main arm 49 is also provided with a rearwardly projecting contact portion 52 which is engaged by a relatively heavy contact spring 53 to thus secure firm electrical contact between the main arm 49 and the corresponding lower stationary terminal which, in the case of Figure 3, is indicated generally by the reference character 7. It is to be noted that the center line of the trunnions 50 is located below and slightly to the left of the center line of the pivot pin 48 so that the lever 49 is urged downwardly due to the weight of the fuse tube and the parts carried thereby and due to the downward thrust from the spring arms 18 which spring arms act in conjunction with the cam member 17. The center lines of the trunnions 50 and of the pivot pin 48 are, however, arranged almost directly above each other so that although a considerable downward thrust may be imparted to the tube 15, only a relatively light turning moment is imparted to the main lever 49. It is also possible, and within the scope of this invention, to so arrange the pivot pin 48 with reference to the trunnions 50 that the center line of the pivot pin is directly above the center line of the trunnions 50, and to rely for the turning moment of the main lever 49 upon the action of the heavy contact spring 53.

The main lever 49 pivotally carries a fuse link extracting and flip-out lever 54 which is provided with a rounded outer portion 55 about which the outer end of the leader 38 of the fuse link extends and is provided with a channel lower portion within which the leader of the fuse link is positioned. The lower inner portion of the fuse tube is slightly rounded, as shown in Figure 3. The fuse link extracting and flip-out lever 54 is curved upwardly at its inner end and is normally located in close proximity to the open lower end of the fuse tube, as shown in Figure 3. It is pivoted to the main lever by means of the pivot pin 56 and is spring urged downwardly towards fuse link extracting motion by the spring 57, one end of which bears directly against the fuse link extracting and flip-out lever 54.

If desired the fuse link extracting and flip-out lever 54 may be provided with a manipulating laterally projecting thumb piece 58, see Figure 1. A fuse link clamping member or lever indicated generally by the reference character 59 is also carried by the pivot 56. It is provided with a shouldered fuse link gripping portion 60 which grips the leader or end of the fuse link between itself and an overhanging portion 61 of the main lever 49. Preferably an outwardly and upwardly curved shield portion 62 is formed on the main lever as shown in Figure 3.

It is to be noted that the spring 57 has its outer end bearing against the fuse link clamping lever or member 59 so that the fuse link clamping member 59 and the fuse link extracting and flip-out lever 54 are urged in opposite directions. It is to be noted that the fuse link extracting and flip-out lever 54 is provided with shouldered ear portions 63 which are adapted to strike the portion 64 of the fuse link gripping lever 59 after the fuse link extracting lever 54 has rocked outwardly a predetermined distance. When the ears 63 of the fuse link extracting lever 54 engage the portion 64 of the fuse link clamping lever 59, these two levers are then interlocked and the force of the spring 57 does not thereafter retain the fuse link clamping lever 59 in clamping po-

sition. Instead these two members move as a unit and release the fuse link so that the fuse link will be thrown substantially directly downwardly from the fuse tube, the momentum acquired by the part 54 under the influence of the spring 57 and gravity being sufficient to carry along the part 59 after the parts 54 and 59 have been locked together.

The main lever 49 is bifurcated and straddles the lower portion of the fuse tube. It is provided with a pair of feet 65 which when the fuse tube has rocked to its lowermost position, engages a portion of the stationary lower contact. The fuse tube transmits the force of the blow due to the fall to the sleeve like portion 46 which is provided with a pair of bearing feet 66, see Figure 6, which engage the main lever 49 at a point substantially directly in line with the feet 65 so that the force of the blow is transmitted from the lower part of the fuse tube substantially directly across the main lever 49 to the lower stationary contact and thus the tendency to bend the main lever 49 is avoided.

The sleeve like portion 46 is provided with an outwardly projecting eyelet like portion 67 and also provided with a pair of spaced arms 68 so that a switch stick may be inserted between the arms 68 and its knob or head like portion may be engaged within the eyelet portion 67 so that the fuse tube may be lifted into or out of position by means of a switch stick. After a fuse tube has operated in response to overload, it may be lifted out from the stationary hook like members 51 by means of the switch stick and may be refused and repositioned by means of the switch stick. Thereafter the switch stick is caused to engage the eyelet portion or manipulating portion 69 which is integral with the upper terminal 20 of the fuse tube and the fuse tube is rocked back into circuit closed position.

After the fuse link has been extracted, it is to be noted that the lever 59 has rocked about the pivot pin 56. During refusing the operator rocks the temporary latching member 69' into a position to engage the shoulder 69" of the lever 59 to thus lock the clamping portion 60 in spaced relation to the portion 61. This facilitates placing the new fuse leader between the clamping member 60 and the cooperating portion 61 during refusing. After the leader has been so placed and the fuse link extracting lever 54 is in the position shown in Figure 3, the temporary latching member 69' is released from the shouldered portion 69" and the clamping member 60 clamps the leader against the member 61.

These features are set forth in considerable detail in my Patent No. 2,378,109 of June 12, 1945 for Fuse Construction.

Each of the fuse units is provided with time delay means for delaying the initial portion of the drop-out motion of the fuse tube and causing the fuse tube to remain in operative position for a predetermined period after the fuse link has blown. This insures clearing of the circuit within the fuse tube prior to the separation of the upper terminal of the fuse tube from the upper stationary terminal, and in addition allows the time delay between the opening of the circuit by one fuse and the closing of the circuit through the succeeding fuse so that if the fault is of a transient nature, it will clear itself before the next succeeding fuse is placed in circuit.

It is obvious that although the invention has been described as relating particularly to repeating fuses, the construction is equally applicable

to a single fuse as it insures a time delay so that the circuit will be completely cleared within the fuse tube prior to the drop-out motion of the fuse tube.

Referring particularly to Figures 3, 5 and 6 it will be seen that the lower stationary contact of each of the fuses is provided with a hood portion 70 which houses a time delay bellows mechanism which consists of a bellows 71 communicating by means of a restricted orifice 72 with a storage bellows 73. The bellows 71 and 72 are joined by means of a connecting member 74 which is peripherally grooved and is supported between a pair of pins 75 carried by the casing 70. The outer end of the bellows 71 is closed by means of a head 76 which is provided with a pair of pivot pins 77 upon which the lower ends of a bifurcated lever 78 are pivoted. The lever 78 is pivoted upon the pivot pin 79 carried by the casing 70 and is provided with an upwardly projecting lip 80 which is adapted to be normally engaged by an adjusting screw 81, the adjusting screw being provided with a lock nut and being adapted to vary the time delay as will appear hereinafter.

The lever 78 carries a small roller 82 which normally is located below the under side of a laterally projecting lip 83 integral with the sleeve 46 of the fuse tube and having a cam like lower surface adapted to ride on the roller 82 when the fuse tube executes drop-out motion. Normally the parts are in the position shown in Figure 3 and the bellows 71 is held in its most extended position by means of the internally located spring 84, see Figure 5. It is clear that if the adjusting screw 81 is projected further to the right as viewed in Figure 3, the roller 82 occupies a lower initial position from that shown in Figure 3 and obviously the length of time that the cam like projecting member 83 engages the roller 82 is shorter and therefore the time delay is lessened.

Assume that all of the fuse tubes are in their operative position. It will be seen that the circuit extends through the first fuse tube 14. If an overload occurs, the fuse link is ruptured and any remaining portion thereof is extracted by the fuse link extracting mechanism. This extracting motion is extremely rapid as the flip-out lever or fuse link extracting lever 54 operates independently of any motion of any other part of the apparatus. However, the fuse tube does not immediately rock out of operative position. Instead the cam like member 83 engages the roller 82 and delays the downward motion of the fuse tube. The liquid within the bellows 71 flows through the restricted orifice 72, see Figure 5, and consequently delays the motion of the roller 82. This liquid flows into the storage bellows which expands to receive the incoming liquid. The roller 82 is thus retarded in its downward motion and consequently the fuse tube is held in contact with the upper resilient spring arms 18. These spring arms follow the fuse tube downwardly a predetermined distance and maintain contact with the upper terminal of the fuse tube.

After the cam like member 83 passes the position shown in Figure 6, it disengages the roller 82 as the cam like member 83 and the lower portion of the fuse tube have an outward and downward rocking motion. Thereafter the fuse tube rocks downwardly to its lowermost position. When the upper terminal 20 of the fuse tube moves away from the head 32 of the plunger 28, the lever 24 is free to rock in a counterclockwise direction as viewed in Figure 3. When the lever rocks, as stated, the projecting portion 27 thereof carries

the pivot point of the first transfer switch 33, 34 outwardly to the position shown in Figure 4. The knob like contacting head on the arm 34 rides on the projection 36 of the first upper stationary terminal and causes the lever to rock against the action of its light restoring spring 35 and causes the knob like contacting portion of the arm 33 of the switch to engage the projecting contact portion 37 of the next of second upper terminal member.

It is to be noted from reference to Figure 3 that the effective lever arm of the spring 36 through which it acts on the lever 24 is smallest when the transfer switch is open and is greatest when the transfer switch is closed. Consequently the force exerted on the transfer switch is a maximum when the switch is closed and a minimum when the switch is open. This lessens the pressure exerted by the plunger 28 on the upper contact of the fuse tube and increases the contact pressure of the transfer switch against the operating stationary contacts 36 and 37 and insures excellent electrical connection between successive upper terminals. The time delay affords adequate time for the circuit to completely clear itself within the fuse tube prior to the disengaging of the upper fuse tube terminal from the upper stationary terminal. In addition to this it allows an interval of time to elapse before the second fuse is put into service and if the fault is of a short duration, it is given an opportunity to clear itself before a new fuse is connected into the circuit. If, on the other hand, the fault has not cleared, the second fuse will drop out after a predetermined interval and the third fuse will be placed in service. Obviously if the fault continues, the third fuse will blow and after a predetermined interval will drop out of circuit. Any number of fuse units may be employed. In the form shown in the drawings three such units have been provided.

In refusing, the lineman lifts the fuse downwardly by means of a switch stick and refuses it and restores it and thereafter rocks it into operative position. If the restored fuse is the first or second fuse in the form shown, it will cause its transfer switch to rock to open position as the plunger 28 will be moved inwardly and will consequently rock the lever 24 inwardly to the position shown in Figure 3.

Time delay mechanism is provided for each of the fuse units.

The time delay feature is not only applicable to repeating fuses but also is applicable to single fuse units. In the event the time delay mechanism is employed in conjunction with a single fuse unit, it insures the complete clearing of the circuit within the fuse tube itself prior to the disengagement of the upper fuse terminal from the upper stationary terminal.

It is to be noted particularly that no flexible leaders or jumpers are required. A good electrical contact is secured by means of the spring arms 48 which engage the sides of the cam member 47 with a heavy contact pressure. They also engage the pins 49 of the upper terminal 20 of the fuse tube with a firm contact pressure and bias the fuse tube downwardly. This downward pressure may be relatively heavy and yet will not excessively strain the fuse link but will produce a pull not exceeding that for which the fuse link is intended.

In addition to this the heavy contact pressure between the knobs or ball-shaped ends of the transfer switch arms and the stationary contacts

provides an excellent electrical connection between successive upper stationary terminals and avoids the necessity of the use of flexible leaders for the transfer switches. The construction, as stated, is such that the effect of the spring 39, see Figure 3, is a maximum when the transfer switch is in closed position and is a minimum when the transfer switch is in open position.

It is to be noted particularly that when the fuse tubes have dropped out of service or have been moved out of service position, the lower stationary contacts and the time delay mechanisms are electrically dead as they are connected to the load line and are disconnected from the power line. Consequently it is possible to adjust the time delay mechanism without any danger to the operator. Where time delay mechanisms are located adjacent the line terminals of the fuse construction, it is impossible to make any adjustment of the time delay mechanism without opening the power line at a point in advance of the fuse construction and thus taking that entire section of the power line out of service until after the adjustment has been made. With the present invention it is possible to make this adjustment and leave the power line in service as described hereinabove.

Other time delay means could be employed. In the form of the invention shown in Figures 7 and 8, the main lever 49 is provided with segment gears 85 which engage pinions 86 rigid with flywheels 87. Obviously paddle wheels could be employed in place of flywheels if so desired. The flywheels 87 and the pinions 86 are mounted on a shaft 88 which is carried by the arm 45 which is rigid with the sleeve 46 secured to the lower portion of the fuse tube. It is apparent that when the fuse link is ruptured, the flip-out mechanism hereinbefore described operates to withdraw any remaining portion of the fuse tube and that the main lever 49 rocks downwardly and starts the rotation of the flywheels 87. This delays the operation of the main lever 49 and consequently delays the drop-out motion of the fuse tube.

In the form of the invention shown in Figures 9 and 10, the fuse tube is provided with a sleeve 89 rigid therewith. The sleeve is integral with a pair of outwardly projecting spaced arms 90 which terminate in downwardly projecting foot portions 91. The portions 91 normally rest upon the main lever 92 which is provided with a pair of outwardly projecting trunnions 93 adapted to be received within the stationary hook-shaped supports 51, see Figure 3, of the lower terminal. The main lever 92 consists in reality of a pair of spaced side portions joined by a transverse web 94.

A housing 95 is pivoted on a transverse pin 96 concentric with the trunnions 93. A spring 97 is positioned around the pin 96 and bears at opposite ends against the web portion 94 of the main lever 92 and the housing 95 and tends to rock the main lever in a clockwise direction and the housing in a counterclockwise direction, as viewed in Figure 9. The housing, it will be noted from Figure 9, is provided with a downwardly projecting stop portion 98 for a purpose hereinafter to appear. The housing 95 is provided with flat shoulder like faces or portions 95'. These portions normally interlock with upstanding fingers 90' integral with the arms 90, as shown in Figure 9. The purpose of this construction will appear hereinafter.

The fuse tube is also provided with a sleeve 99

rigid therewith and spaced from the lower end of the fuse tube. This sleeve is integral with a pair of inwardly projecting arms 100 which are pivoted by means of the screws 101 to a pair of auxiliary levers 102 pivoted on the pin 103 carried by the housing 95. The screws 101 extend into the head portion 104 of the time delay bellows 105, the storage bellows being indicated by the reference character 106. The intermediate portion 107 is carried between a pair of pins 108 10 passing through the housing. The bellows construction is the same as that disclosed in Figure 5 and hereinbefore described.

The leader of the fuse link is clamped by means of the thumb nut 109 to the main lever 92. If desired, the lever 92 may be provided with a pair of guiding fingers 110 between which the fuse link extends.

When the fuse link is ruptured, the lever 92 will rock downwardly and act in the manner of a flip-out lever to quickly withdraw any remaining portion of the fuse link. When the lever 92 rocks downwardly, it will move away from the foot portion 91. The fuse tube will move downwardly, being urged downwardly by means of the upper stationary contact not shown but hereinbefore described, and this downward motion will be retarded by means of the time delay bellows mechanism. The members 90' and the portions 95' will remain in sliding engagement with each other for a predetermined interval of time and finally the members 90' will pass from the portions 95' and the fuse tube is then free to rock outwardly at its lower portion due to the collapsing of the toggle mechanism formed by the projecting portions 100 and the levers 102. The upper terminal of the fuse tube will now disengage itself from the upper stationary terminal.

The lip 98 of the housing 95 provides a stop against which the arms 100 of the sleeve 99 normally bear.

In all forms of the invention a restoring spring corresponding to the spring 84, see Figure 5, is provided for the main bellows and in all forms of the invention it is to be understood that the time delay bellows mechanism is filled with a suitable liquid which will withstand temperature changes and which will be sufficiently fluid under all conditions to pass from the main bellows to the storage bellows through a restricting orifice.

In all forms of the invention the time delay is so proportioned as to insure clearing of the circuit within the fuse tube prior to the disengagement of the upper terminal of the fuse tube from the upper stationary terminal.

Any form of the invention may be used either as a single fuse structure or as a repeating fuse construction.

Although this invention has been described in considerable detail, it is to be understood that such description is intended as illustrative rather than limiting, as the invention may be variously embodied and is to be interpreted as claimed.

I claim:

1. A repeating drop-out fuse construction comprising a plurality of fuse units each including upper and lower terminals, an insulating fuse tube mounted for drop-out motion, and a fuse link normally connecting the upper and lower terminals; transfer switches for connecting successive upper terminals; normally inactive spring actuated means controlled by the fuse tubes for closing the corresponding transfer switch when a fuse tube executes drop-out motion, said spring

actuated means being arranged to produce their greatest effect when said transfer switches are in closed position to thereby produce high contact pressure; mechanism for each fuse tube controlled by the fuse link of such fuse tube for normally holding the fuse tube in operative position and releasing the fuse tube for drop-out motion upon rupture of the fuse link; and time delay means adjacent the lower portion of said fuse tubes arranged to hold each fuse tube in operative position for a predetermined interval of time after rupture of the corresponding fuse link.

2. A repeating drop-out fuse construction comprising a plurality of fuse units each including upper and lower terminals, an insulating fuse tube, and a fuse link within said fuse tube normally connecting said upper and lower terminals; said fuse tubes being biased for drop-out motion and being normally restrained by the corresponding fuse links; transfer switches adjacent the upper terminals for connecting successive upper terminals; movable switch supporting means supporting said transfer switches, said transfer switches being pivoted on said switch supporting means and arranged for rotary and translatory motion, each switch supporting means being under the control of a fuse tube; and time delay means for delaying the connecting of successive terminals.

3. A repeating drop-out fuse construction comprising a plurality of fuse units each including upper and lower terminals, an insulating fuse tube, and a fuse link within said fuse tube normally connecting said upper and lower terminals; said fuse tubes being biased for drop-out motion and being normally restrained by the corresponding fuse links; transfer switches adjacent the upper terminals for connecting successive upper terminals; movable switch supporting means supporting said transfer switches, said transfer switches being pivoted on said switch supporting means and arranged for rotary and translatory motion, each switch supporting means being under the control of a fuse tube; and time delay means for delaying the drop-out motion of said fuse tubes.

4. A repeating drop-out fuse construction comprising a plurality of fuse units each including upper and lower terminals, an insulating fuse tube, and a fuse link within said fuse tube normally connecting said upper and lower terminals; said fuse tubes being biased for drop-out motion and being normally restrained by the corresponding fuse links; each of said upper terminals having stationary contacts; transfer switches adjacent the upper terminals for connecting successive upper terminals, each of said transfer switches having contacting portions at each of the ends thereof adapted to engage the stationary contacts of a pair of upper terminals, and movable supporting means for each transfer switch biased towards switch closed position, each transfer switch being pivoted intermediate its ends to the corresponding supporting means and each of said transfer switches being under the control of a fuse tube.

5. A repeating drop-out fuse construction comprising a plurality of fuse units each including upper and lower terminals, an insulating fuse tube, and a fuse link within said fuse tube normally connecting said upper and lower terminals; said fuse tubes being biased for drop-out motion and being normally restrained by the corresponding fuse links; each of said upper ter-

minals having stationary contacts; and transfer switches mounted for rotary and translatory motion adjacent the upper terminals for connecting successive terminals, each of said transfer switches having contacting portions at each of the ends thereof adapted to engage the stationary contacts of a pair of upper terminals; movable supporting means for supporting said transfer switches; means biasing said supporting means towards motion; each of said supporting means being under the control of a fuse tube.

6. A repeating drop-out fuse construction comprising a plurality of fuse units each including upper line terminals and lower load terminals, an insulating fuse tube mounted for downward and outward rocking motion, and a fuse link within said fuse tube normally connecting said upper and lower terminals; said fuse tubes being biased for drop-out motion and being normally restrained by the corresponding fuse links; transfer switches adjacent the upper terminals for connecting successive upper terminals, each of said transfer switches being under the control of a fuse tube and arranged to automatically close upon drop-out motion of the corresponding fuse tube; said fuse tubes having projecting portions; time delay means for each fuse tube, each time delay means including a movable member normally located below the projecting portion of the corresponding fuse tube and bellows mechanism for delaying the motion of the corresponding movable member, said bellows mechanism having a restricted escape orifice, each time delay means being connected to the corresponding lower terminal and being electrically dead after the corresponding fuse tube has rocked downwardly and outwardly.

7. A repeating drop-out fuse construction comprising a plurality of fuse units each including upper line terminals and lower load terminals, an insulating fuse tube mounted for downward and outward rocking motion, and a fuse link within said fuse tube normally connecting said upper and lower terminals; said fuse tubes being biased for drop-out motion and being normally restrained by the corresponding fuse links; transfer switches adjacent the upper terminals for connecting successive upper terminals, each of said transfer switches being under the control of a fuse tube and arranged to automatically close upon drop-out motion of the corresponding fuse tube; said fuse tubes having projecting portions; time delay means for each fuse tube, each time delay means including a movable member normally located below the projecting portion of the corresponding fuse tube and bellows mechanism for delaying the motion of the movable member, said bellows mechanism having a restricted escape orifice; and means for adjusting the initial position of said movable members, each time delay means being connected to the corresponding lower terminal and being electrically dead after the corresponding fuse tube has rocked downwardly and outwardly.

8. A repeating drop-out fuse construction comprising a plurality of fuse units each including upper line terminals and lower load terminals, an insulating fuse tube mounted for downward and outward rocking motion, and a fuse link within said fuse tube normally connecting said upper and lower terminals; said fuse tubes being biased for drop-out motion and being normally restrained by the corresponding fuse links; transfer switches adjacent the upper terminals for connecting successive upper terminals, each

of said transfer switches being under the control of a fuse tube and arranged to automatically close upon drop-out motion of the corresponding fuse tube; slidably related interlocking means for normally preventing the outward motion of the lower ends of said fuse tubes and detachable when said fuse tubes have moved downwardly a predetermined distance to permit outward motion of the lower ends of said fuse tubes; and time delay means for delaying the downward motion of said fuse tubes, each time delay means being connected to the corresponding lower terminal and being electrically dead after the corresponding fuse tube has rocked downwardly and outwardly.

9. A drop-out fuse construction comprising an upper line terminal and a lower load stationary terminal, an insulating fuse tube normally occupying an operative position and adapted to move to an inoperative position, a fuse link within said fuse tube normally connecting said terminals, supporting mechanism controlled by said fuse link for supporting said fuse tube in operative position and adapted to release said fuse tube for drop-out motion on rupture of said fuse link; said fuse tube having a projecting portion, a movable member adapted to be engaged by said projecting portion upon rupture of said fuse link for controlling the drop-out motion of said fuse tube, and time delay bellows mechanism for delaying the action of said movable member, said time delay bellows mechanism having a restricted escape orifice, said time delay bellows mechanism being connected to the corresponding lower terminal and being electrically dead after said fuse tube has moved to inoperative position.

10. A drop-out fuse construction comprising an upper and a lower stationary terminal, an insulating fuse tube normally occupying an operative position and adapted to move to an inoperative position, a fuse link within said fuse tube normally connecting said terminals, supporting mechanism controlled by said fuse link for supporting said fuse tube in operative position and adapted to release said fuse tube for drop-out motion on rupture of said fuse link, said fuse tube having a projecting portion, a movable member adapted to be engaged by said projecting portion upon rupture of said fuse link for controlling the drop-out motion of said fuse tube, time delay bellows mechanism for delaying the action of said movable member, said time delay bellows mechanism having a restricted escape orifice, and means for adjusting the initial position of said movable member.

11. A drop-out fuse construction comprising an upper line terminal and a lower load stationary terminal, an insulating fuse tube normally occupying an operative position and adapted to move downwardly and outwardly to inoperative position, a fuse link within said fuse tube normally connecting said terminals, supporting mechanism normally supporting said fuse tube in operative position and controlled by said fuse link and releasing said fuse tube for drop-out motion upon rupture of said fuse link, slidably related interlocking means normally holding said fuse tube against outward motion and permitting downward motion of said fuse tube, and retarding bellows mechanism delaying the downward motion of said fuse tube, said bellows mechanism having a restricted escape orifice, said bellows mechanism being connected to the corresponding lower terminal and being electrically

dead after said fuse tube has moved to inoperative position.

12. A repeating drop-out fuse construction comprising a plurality of fuse units adapted to be successively connected in an electric circuit, each fuse unit including upper and lower terminals, an insulating fuse tube mounted for drop-out motion, and a fuse link normally connecting the upper and lower terminals; transfer switches for successively connecting said fuse units in said circuit, each transfer switch being controlled by a fuse tube; normally inactive spring actuated means controlled by the fuse tubes for closing the corresponding transfer switch when a fuse tube executes drop-out motion, each spring actuated means including a pivoted lever and a spring secured at one end to said lever and fixed at its other end in spaced relation to said lever and arranged to have an increasing effective lever arm as said transfer switch approaches closed position whereby said spring actuated means will produce their greatest effect when said transfer switches are in closed position to thereby produce high contact pressure; mechanism for each fuse tube controlled by the fuse link of such fuse tube for normally holding the fuse tube in operative position and releasing the fuse tube for drop-out motion upon rupture of the fuse link; and time delay means for holding said fuse tubes in operative position for a predetermined interval of time after rupture of the corresponding fuse link.

13. A repeating drop-out fuse construction comprising a plurality of fuse units each including upper and lower terminals, an insulating fuse tube mounted for drop-out motion, and a fuse link normally connecting the upper and lower terminals; transfer switches for connecting successive upper terminals; normally inactive spring actuated means controlled by the fuse tubes for closing the corresponding transfer switch when a fuse tube executes drop-out motion, said spring actuated means being arranged to produce their greatest effect when said transfer switches are in closed position to thereby produce high contact pressure; and mechanism for each fuse tube controlled by the fuse link of such fuse tube for normally holding the fuse tube in operative position and releasing the fuse tube for drop-out motion upon rupture of the fuse link.

14. A repeating drop-out fuse construction comprising a plurality of fuse units adapted to be successively connected in an electric circuit, each fuse unit including upper and lower terminals, an insulating fuse tube mounted for drop-out motion, and a fuse link normally connecting the upper and lower terminals; transfer switches for successively connecting said fuse

units in said circuit, each transfer switch being controlled by a fuse tube; normally inactive spring actuated means controlled by the fuse tubes for closing the corresponding transfer switch when a fuse tube executes drop-out motion, said spring actuated means being arranged to produce their greatest effect when said transfer switches are in closed position to thereby produce high contact pressure; and mechanism for each fuse tube controlled by the fuse link of such fuse tube for normally holding the fuse tube in operative position and releasing the fuse tube for drop-out motion upon rupture of the fuse link.

15. A repeating drop-out fuse construction comprising a plurality of fuse units each including upper and lower terminals, an insulating fuse tube, and a fuse link within said fuse tube normally connecting said upper and lower terminals; said fuse tubes being biased for drop-out motion and being normally restrained by the corresponding fuse links; each of said upper terminals having stationary contacts; transfer switches mounted for rotary and translatory motion adjacent the upper terminals for connecting successive terminals, each of said transfer switches having contacting portions at each of the ends thereof adapted to engage the stationary contacts of a pair of upper terminals; movable supporting means for supporting said transfer switches; and means biasing said supporting means towards switch closed position; each of said supporting means being under the control of a fuse tube.
